UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,814, dated October 29, 1895.

Application filed September 27, 1895. Serial No. 563,928. Term of patent 3½ years.

To all whom it may concern:

Be it known that I, CHARLES BOOZ, a citizen of the United States, residing at Buffalo, in the county of Erie and State of New York,

5 have invented and produced a new and original Design for Wall-Paper, of which the following is a specification, reference being had to the accompanying drawing, showing a part thereof.

10 The design consists of a series of large ornaments formed of ornamental scrolls with small ornamental panels inside of and interlacing with the large ornaments and sprays of flowers and leaves in the center of said ornaments,

15 as represented in the accompanying drawing. The border of said design consists of large ornaments formed of similar ornamental scrolls filled with flowers and leaves and small ornamental scrolls interlacing with said ornaments, as shown in the drawing.

20

What I claim is—

1. The design for wall paper herein shown and described.

2. In the design for wall paper the border herein shown and described.
